OUTDOOR LUMINAIRE

Reynolds B. Winslow, Syracuse, N.Y., assignor to Crouse-Hinds Company, Syracuse, N.Y., a corporation of New York

Filed Jan. 26, 1967, Ser. No. 5,577

Term of patent 14 years

(Cl. D48—31)

FIG. 3

FIG. 2

FIGURE 1 is an elevational view of one side of the luminaire showing my new design. The luminaire is of square configuration and the remaining three sides are each a mirror image of the side shown.

FIGURE 2 is a reduced top plan view of the luminaire shown in FIGURE 1.

FIGURE 3 is a bottom plan view of the luminaire shown in FIGURES 1 and 2.

The cross-hatch shading in FIGURE 3 is representative of a conventional screen pattern and is understood to be continuous throughout the areas so shaded. The broken line showing of a support pole in FIGURES 1 and 3 is for illustrative purposes only.

I claim:

The ornamental design for outdoor luminaire, as shown and described.
